(57) **CLAIM**

The ornamental design for a display screen with a graphical user interface, as shown and described.

DESCRIPTION

FIG. 1 illustrates a front view of a display screen with a graphical user interface according to a first embodiment of the claimed design;

FIG. 2 illustrates a front view of a display screen with a graphical user interface according to a second embodiment of the claimed design;

FIG. 3 illustrates a front view of a display screen with a graphical user interface according to a third embodiment of the claimed design;

FIG. 4 illustrates a front view of a display screen with a graphical user interface according to a fourth embodiment of the claimed design;

FIG. 5 illustrates a front view of a display screen with a graphical user interface according to the fourth embodiment of the claimed design, shown in a differing broke-line context than that of FIG. 4;

FIG. 6 illustrates a front view of a display screen with a graphical user interface according to a fifth embodiment of the claimed design;

FIG. 7 illustrates a front view of a display screen with a graphical user interface according to the fifth embodiment of the claimed design, shown in a differing broke-line context than that of FIG. 6;

FIG. 8 illustrates a front view of a display screen with a graphical user interface according to the fifth embodiment of the claimed design, shown in a differing broke-line context than those of FIG. 6 and FIG. 7;

FIG. 9 illustrates a front view of a display screen with a graphical user interface according to a sixth embodiment of the claimed design;

FIG. 10 illustrates a front view of a display screen with a graphical user interface according to the fourth embodiment of the claimed design, shown in a differing broke-line context than those of FIG. 4 and FIG. 5; and,

FIG. 11 illustrates a front view of a display screen with a graphical user interface according to the fourth embodiment

(Continued)

of the claimed design, shown in a differing broke-line context than those of FIG. 4, FIG. 5, and FIG. 10. The dashed broken lines illustrate environmental features, such as a border of the graphical user interface or portions thereof, that form no part of the claimed design. The outermost dot-dash broken-line perimeter illustrates a display screen or portion thereof and forms no part of the claimed design.

1 Claim, 11 Drawing Sheets
